UNITED STATES PATENT OFFICE.

FREDERIC E. BERTRAND, OF LYNN, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING UPON SOLES.

Application filed March 9, 1925. Serial No. 14,149.

The present invention relates to machines for operating upon shoe parts, such as soles, and is herein illustrated as embodied in a machine of the type of the well-known, commercial Goodyear insole toe snipping machine as disclosed in United States Letters Patent No. 1,087,578, granted February 17, 1914, upon application of John B. Hadaway. Machines of this type are commonly employed to form cuts in an insole adjacent to the toe and transversely of the channel flaps or lips which have been already formed, or which are subsequently to be formed, by a channeling operation upon the insole.

An important desideratum in such machines is to provide means by the use of which a sole, and particularly a relatively flimsy or flexible insole, will be positioned accurately and with certainty not only angularly but also longitudinally and laterally with respect to a plurality of tools or to a single tool.

Accordingly, the present invention provides means by the use of which not only will a sole, placed upon a work table, be thus positioned in its own plane, but also an operating tool or tools will likewise be positioned with respect to such a sole. It is important for securing a high quality of product, in case of a plurality of tools or of a single tool with an elongated operating portion, that the tools or the elongated portion of the tool shall occupy a definite, predetermined relation to some line or contour of the sole. For example, the axis of the edge of a snipping cutter should preferably be substantially perpendicular to a tangent to the curved line of the channel at the toe of an insole.

Hence, in order that a shoe part, such as an insole, may be presented accurately in proper relation to an operating tool or tools, in accordance with one feature of the present invention, there is provided a work support or table and means for supporting it for movement about an axis substantially perpendicular to the work engaging surface of the table together with a tool having an elongated operating portion, the tool being movable angularly with the table and also movable independently toward and from the table, and gaging

means mounted on the table for positioning the work by engagement with opposite edges thereof. The illustrated machine 55 comprises gaging devices for engaging the edge of a sole, which devices, together with the operating tool or tools and the work support, are movable angularly in response to pressure exerted through the sole so that the 60 sole will be brought with certainty in predetermined relation to the gaging devices and thereby to the tool.

Inasmuch as insoles to be operated upon may be relatively flimsy, a feature of the invention comprises improved work gaging mechanism including means for limiting the maximum degree of pressure which may be exerted by the gages upon the work. More specifically, there is provided in the illustrated machine a clutch and means tending to maintain the clutch inoperative and also a single actuator through which not only may a pair of gages be moved into engagement with opposite edges of a sole but the 75 clutch may also be thrown into operation. Preferably, the construction and arrangement are such that the operator, by moving a treadle or other lever, will first bring one or more pairs of edge gages into engagement with the sole and cause them to exert an increasing pressure thereon until the predetermined force by which the clutch is being held out of operation has been overcome after which the clutch will be thrown 80 into operation but the operator can thereafter exert no greater pressure upon the edge of the sole and thus any curling up of the edge of the sole is avoided.

Another feature of the present invention 90 relates to improved cutter supporting and operating mechanism which, as illustrated, comprises a cutter holder and connections therefrom to a rotary work table including a pair of parallel links for supporting and 95 guiding the holder together with means for moving the holder in substantially a rectilinear path toward and from the table.

In addition to the features already referred to, the present invention comprises 100 also other combinations and arrangements and details of construction which will now be described in connection with the accompanying drawings, which illustrate a pre-

ferred embodiment of the invention, and will then be pointed out in the appended claims.

In the drawings:

5 Fig. 1 is a side elevation of a machine which is particularly adapted for snipping or slashing the toe ends of insoles, the supporting column of the machine being omitted;

10 Fig. 2 is a plan view, partly in section, showing the work table and sole positioning devices of the machine;

15 Fig. 3 is a view in end elevation, partly in section, of substantially the same portion of the machine;

20 Fig. 4 is a view in perspective of the knife holder; and

25 Fig. 5 is a detail view of a modified form of one of the side gages which includes a holdown that may be employed for particularly flimsy or flexible insoles.

30 In certain respects the present invention is a further development of the invention disclosed and claimed in applicant's prior application, Serial No. 606,879, filed December 14, 1922.

35 As illustrated, the frame of the machine includes a head 10 from which extends forwardly a base plate having a socket 12 in which lies a ball bearing 14 for the base 16 of a work support or table 18 which base has a depending hub 20. Upon the upper, horizontal surface of the table is secured a toe gage 26 while two pairs of side gages, in the form of pins 28, extend through slots 30 in the table. These side gages are secured to the upper arms of bell crank levers 32 pivoted upon pins 34 which are secured by set-screws 36 to the table unit. The two bell cranks of each pair are connected to move together by segment gears 38. The lower arm of one of the bell cranks of each pair is provided with a slot 40 in which slides a pin 42 which, as shown particularly in Fig. 2, is mounted in an equalizing lever 44 pivoted at 46 in the head 48 of a stem 50 which is freely movable vertically in a sleeve 52 fitting within the hub 20. A coiled spring 54 bearing against the lower end of the slide 50 and resting against an adjustable screw 56 threaded into the lower end of the sleeve 52 tends constantly to hold the gages of each pair separated, their outward movement about the pins 34 being limited by adjustable screws 58. The stem 50 is caused to rotate with the sleeve 52 by a key 60 while the sleeve 52 is caused to rotate with the hub 20 by a screw 62.

60 The mechanism by which the edge gages are brought into engagement with an insole, such as is indicated at I in Fig. 2, comprises a lever 66 in which is secured a button 68 resting upon the top of the head 48 and pivoted at 70 to a bell crank lever 71 in turn pivoted upon the machine frame at 72 and

connected by a link 74 to a lever 76 forming part of a clutch actuating mechanism which is designated generally by the character 78 and which includes a coiled spring 80 that constantly exerts a predetermined force upon one of the members of the clutch 81 and tends to maintain the clutch normally out of operation. The clutch members are carried upon a main shaft 82 which is connected through the clutch to a loose driving pulley 84. The mechanism by which the edge gages 28 are pressed against the edge of the sole I, against the resistance of spring 54, and by which also the clutch is thrown into operation against the resistance of spring 80 comprises a rod 88 having an enlarged head 90 connected to the lever 66 at 92 and actuated through a treadle (not shown). This rod 88 passes through an adjustable, threaded sleeve 94 screwed into a part of the machine frame. A collar 96 secured to the rod 88, by coming into engagement with the lower face of sleeve 94, limits the upward movement of the rod while its downward movement is limited by the engagement of head 90 with sleeve 94. Normally the edge gages 28 are held in separated position, determined by the screws 58, and the clutch is held out of operative position by springs 54 and 80, the collar 96 being in engagement with the sleeve 94. During the depression of the treadle and of the rod 88, the relatively light spring 54 is compressed and the edge gages 28 are brought into engagement with the edge of the sole and caused to exert thereon an increasing pressure. The relative strengths of springs 54 and 80 and the adjustment of screw 56 are preferably so proportioned that after the pressure exerted by the four edge gages upon the sole has reached a predetermined amount, as, for example, for a particular quality of insoles, somewhat less than half a pound at each gage, the resistance of spring 80 is overcome so that further depression of the treadle causes the clutch 81 to be thrown into operation, whereupon the head 90 of rod 88 comes into engagement with the sleeve 94 with the result that, even if the attendant continues to press the treadle, there can be no increase in the pressure exerted by the gages 28 upon the insole. By adjusting screw 56, the force exerted by spring 54 against inward movement of the gages and consequently the maximum pressure which can be exerted by the gages upon the insole through the depression of the treadle, before the clutch is thrown in, can be adjusted. A greater variation in the maximum pressure may be secured by substituting a heavier or lighter spring for the spring 54.

65 The clutch 81 and its actuating mechanism 78 may be, and as shown are, of a well known type, similar, for example, to that

fully disclosed in Letters Patent No. 1,087,578, above referred to. This construction is such that, at the end of a single revolution of the main shaft 82 and after a 5 single cutting stroke of the operating tools, the clutch will be automatically rendered inoperative.

As illustrated, the operating tools comprise a knife 97 provided with a V-shaped cutting edge and a horizontally adjustable L-shaped knife 98 having a straight cutting edge. These two knives are each independently secured by clamping screws to their respective knife blocks 99, 100 and each of these blocks is independently adjustable vertically by means of screws 101 which fit slots 102 in a knife holder 103. The lower end of a plate 104 which forms a part of the knife holder and lies between the two knife blocks 20 constitutes a presser foot with relation to which each knife block and the knife clamped therein is adjustable vertically to vary the depth to which the knives can penetrate the insole. After the knife blocks 25 have been adjusted to the desired vertical position by screws 101, they are clamped in such position and to the knife holder by a single clamping stud or screw 105 which is threaded into the knife block 100 through 30 slots in the knife block 99 and in the plate 104. It will be noted that with this construction, by taking out the clamping stud 105, the knife blocks with their knives clamped thereto may readily be removed 35 from the machine for sharpening or other purposes and then may be replaced without loss of adjustment. The knife holder 103 is supported and guided to move in a substantially vertical line by a pair of parallel 40 links 106 pivoted to the knife holder 103 at 107, 108 and to a bracket 109, extending upwardly from table 18, upon fulcrum 110, 111. It may be noted that, in order to provide a compact and effective arrangement, the axis 45 of the knife holder is somewhat in the rear of the axis about which it and the work table turn with the result that during such turning the point of contact between the tool holder and the button 120, below referred to, shifts slightly laterally. A spring 50 112, connected to an extension of one of the links 106, tends to hold the links and the knife holder in their uppermost position determined by the engagement of a lug 117 upon one of the links with a stop screw 118 threaded into the bracket 109. For imparting to the knives and their holder an operative cutting stroke toward and from the work table 18, there is provided a bell crank 55 lever 122 which is provided with a button 120 to engage the upper end of the tool holder and which is pivoted to the frame at 124. Pivoted at 126 in a forked portion of the lever 122 is a block 128 through which

passes an eccentric rod 132 having an enlarged head 130 to engage the block 128 with which it is normally held in contact by a coiled spring 134 interposed between the block 128 and check nuts 136 upon rod 132 which is actuated by an eccentric 138 upon the main shaft 82. With this construction, it will be noted that the knife holder 103 is free to adjust itself angularly with the table 18 about the vertical axis of the table so that in whatever position the holder may be it can 75 be operated by the lever 122 and its actuating mechanism.

As shown in Fig. 5, when the machine is to be employed to operate on particularly flimsy or flexible insoles, some or all of the 80 gage pins 28 may each be provided with a holdown in the form of an arm 140 secured adjustably, as by a set screw 142, to the gage pin and preferably at such a distance from the table 18 that the holdown 140 will be 85 nearly or actually in contact with the upper face of the insole when the gage is in contact with the insole edge and thus restrain the insole from curling or buckling.

The manner in which the machine operates has been already indicated but it will now be described briefly. The parts being in the position shown in Figs. 1 and 3, the operator places an insole I upon the table 18 and presses its toe end continuously against the toe gage 26. He then depresses the treadle until all of the side gages 28 come into contact with the edge of the insole. If one of the gages of either pair, during such depression, engages the insole before the companion gage, it will push the forepart of the insole laterally along the table into contact with the companion gage. If both of the gages of a pair contact with the insole before both of the gages of the other pair have done so, continued movement of the treadle acting through the equalizer 44 will finally bring all four of the side gages into contact with the insole. If during this actuation of the side gages the insole should be so held by the operator that the median line of the forepart of the insole did not coincide with the median line determined by the four side gages, then the fourth gage 110 would still be out of contact with the insole when the third gage had come into such contact and the further movement of the treadle would cause the table 18 with the tool holder 103 and its associated parts to turn on its ball bearing 14 about the axis of the table until the fourth gage made such contact and until such coincidence was effected, so that finally, under all circumstances, the insole is accurately centered with respect to the gages and with respect to the snipping knives, thus insuring an exact, unvarying location of the insole on the table longitudinally, laterally and angularly.

When the pressure exerted by the gages upon the insole has reached a predetermined amount as already explained, the resistance of the clutch spring 80 is overcome and the clutch is thrown into operation, whereupon the head 90 of the rod 88 comes into contact with the sleeve 94 so that additional pressure exerted upon the treadle can not be transmitted to the insole. While the insole is so located, the tool holder 103 is depressed through the action of the eccentric 138. The knives 97, 98 enter the insole to a depth determined by the relative location of the knives and presser foot 104. Thereafter any further movement of the rod 132 causes head 130 to move away from block 128, the spring 134 being compressed, so that each of the cuts in the insole has a depth which is predetermined although it may be varied as desired through independent adjustment of screws 101. The knife holder 103 then returns to the position shown in Fig. 1 under the influence of spring 112 and the clutch is automatically thrown out of operation, the treadle being released to permit its connected mechanism to return to the position shown in Fig. 3.

Having thus indicated the nature and scope of the invention and having described in detail a machine in which it has been embodied, what I claim as new and desire to secure by Letters Patent of the United States is:

1. A machine for operating upon soles having, in combination, a frame, a work table and a power shaft mounted in the frame, said table being freely rotatable about a substantially vertical axis, while a sole is being located on the table, a bracket carried by said table, a cutter having an elongated cutting edge and carried by said bracket and constructed and arranged for movement substantially parallel to said axis toward and from said table, and operative connections between said power shaft and said cutter.

2. In a machine for operating upon soles, the combination of a horizontal work support freely movable about a vertical axis which passes through said support adjacent to the operating point, a cutter carried by and movable angularly with said support, and power mechanism for moving said cutter substantially parallel to said axis toward and from said support.

3. In a machine for operating upon parts of shoes, the combination of a work table, means for supporting said table constructed and arranged to permit movement thereof about an axis substantially perpendicular to the work engaging surface of the table, a tool having an elongated operating portion and being movable angularly with said table and also movable independently to-

ward and from the table, and gaging means mounted on the table for positioning the work by engagement with opposite edges thereof.

4. In a machine for operating upon soles, the combination of a work table, a reciprocating tool having an elongated operating portion, gaging devices for engaging opposite edges of a sole supported by the table, said table, tool and gaging devices being movable angularly together while said devices are successively engaged with the sole.

5. In a machine for operating upon soles, the combination of a work table, a tool having an elongated operating end and being movable substantially perpendicular to the sole engaging surface of the table, an end gage, two pairs of side gages for engaging opposite edges of the sole, said table, tool and gages being angularly movable together, and means for relatively operating said gages to cause them to centralize the sole with respect to the tool.

6. A machine for operating upon soles having, in combination, a frame, an angularly movable work table, a tool having an elongated operating end and being movable angularly with the table, means for supporting the table constructed and arranged to permit movement of the table through a substantial arc about an axis substantially perpendicular to and intersecting the sole engaging surface of the table, and gaging means for opposite edges of the sole.

7. In a machine for operating upon soles, the combination of a work table, a slitting cutter carried by the table, said table and cutter being mounted for rotation about an axis intersecting the line determined by the edge of the cutter, an end gage and two pairs of side gages movable with the table, means including an equalizer for moving all of the side gages into contact with the edge of a sole supported upon the table, and means for moving the cutter toward and from the sole.

8. In a machine for operating upon soles, the combination of an angularly movable work table, a plurality of cutters carried by and movable angularly with said table and constructed and arranged to form a plurality of cuts adjacent to the toe of an insole, and means for moving said cutters toward and from an insole supported upon the table.

9. In a machine for operating upon parts of shoes, the combination of a work support, a tool carried by and movable angularly with said support and also movable independently toward and from the support, and a plurality of pairs of connected positioning gages movable relatively to the support to determine the position of the work.

10. In a machine for operating upon soles, the combination of a work table, a cutter

- having an elongated edge and carried by and angularly movable with said table and also movable independently toward and from the table, and a plurality of pairs of 5 connected positioning gages movable with respect to the table to determine the position of a sole, and means for moving all of said gages into engagement with the sole.
11. In a machine for operating upon soles, 10 the combination of a horizontal sole support, an operating tool movable toward and from said support, a toe gage on said support, two pairs of connected side gages movable about horizontal axes into engagement 15 with the edge of a sole upon said support, one pair being located near the toe gage and another pair further therefrom, and means including an equalizer for moving the side gages into engagement with the sole.
12. In a machine for operating upon soles, 20 the combination of a sole support movable through a substantial arc, a tool having an elongated operating end and being carried by the support and constructed and arranged 25 to operate in a definite angular relation to a sole upon said support, a plurality of gages movable with said support, and means for moving said gages and tool successively into engagement with the sole while permitting 30 angular movement of the tool and support.
13. In a machine for operating upon soles, 35 the combination of a rotary work table, a cutter having an elongated cutting edge, a holder for the cutter, connections including parallel links between said table and said holder, and means for moving the holder in substantially a rectilinear path toward and from said table.
40. A machine for operating upon soles having, in combination, a frame, a work table supported by and angularly movable in the frame, a gage constructed and arranged for movement to and from the edge 45 of a sole supported on the table, a lever supported on the frame against angular movement with the table, and operative connections between the lever and the gage by which the gage may be moved into engagement with the sole.
15. A machine for operating upon soles 55 having, in combination, a frame, a power shaft, a horizontal work table movable through a substantial arc about a vertical axis, a tool movable angularly with the table and also movable independently toward and from the table, gages constructed and arranged for movement toward and from the edge of a sole supported on the 60 table, operative connections between the power shaft and the tool, and means including parts supported on the frame through which the gages may be moved toward and from the sole.
65. 16. A sole positioning device having, in combination, a sole support, a plurality of pairs of connected positioning gages movable about axes substantially parallel to the sole-engaging surface of said support into and out of engagement with a sole upon said support, yielding means acting normally to move the gages away from the sole, and means including an equalizing device through which all of the gages may be moved into engagement with the sole.
17. In a machine for operating upon soles, 70 the combination of a clutch, means tending to maintain the clutch inoperative, a work support, a pair of movable edge gages, and a single actuator through which the gages may be moved into engagement with opposite edges of a sole and the clutch thrown into operation.
18. In a machine for operating upon soles, 75 the combination of a clutch, means tending to hold the clutch in inoperative position, a work support, a gage movable laterally along said support toward and from a sole lying thereon, and a single actuator through which the gage is first moved into engagement with the edge of the sole and then, after the gage has exerted a predetermined pressure thereon, the clutch is thrown into operation.
19. A machine for operating upon shoe parts, 80 the combination of a plurality of gages movable into and out of contact with the work, means through which a predetermined but adjustable force may be exerted upon said gages to resist movement thereof into engagement with the work, and means controlled by the operator for overcoming that force and pressing the gages against the work with a predetermined pressure.
20. In a machine for operating upon soles, 85 the combination of a clutch, actuating means therefor constructed and arranged to exert a predetermined resistance against the throwing of the clutch into operation, a pair 90 of gages movable into and out of contact with the edge of a sole, means controlled by the operator for pressing the gages against the sole edge with an increasing pressure, and connections from said means to the 95 clutch actuating means so constructed and arranged that the clutch will be thrown into operation as soon as the gages exert a predetermined pressure upon the sole.
21. An insole toe snipping machine having, 100 in combination, a frame, a power shaft, a clutch, a work table, a plurality of snipping cutters, a holder in which said cutters are adjustably secured, said table and holder being movable together in the frame through a substantial arc, a plurality of gages movable toward and from the edge of an insole supported upon the table, connections from 105 said shaft to said holder for moving the cutters in substantially a rectilinear path to-

ward and from the insole, and means controlled by the operator for pressing the gages against the sole edge with a predetermined pressure upon the attainment of which the clutch is thrown automatically into operation.

22. In a machine for operating upon soles, the combination of a work support, a pair of gages, means through which said gages 10 may be pressed against opposite edges of a sole and a holdown secured to each gage and arranged to extend over the face of the sole and also having provision for adjustment according to the thickness of the sole.

23. In a machine for operating on insoles, the combination of a work support, a plurality of gages movable toward and from the edge of an insole lying on said support, mechanism through which an operator may 20 press said gages against the edge of the insole including means for equalizing and limiting the degree of pressure exerted by the several gages on the insole whatever the force exerted by the operator on said mechanism 25 may be, and means by which the maximum pressure may be adjusted.

24. In a machine for operating on insoles, the combination of a work support, two pairs of gages movable toward and from the 30 edge of an insole lying on said support, means tending normally to hold said gages in inoperative position, and mechanism by which an operator may press said gages against the edge of the insole including 35 means for equalizing and limiting the degree of pressure exerted by the several gages on the insole whatever the force of the pressure exerted by the operator may be.

25. In a machine for operating upon soles, the combination of a work support, a pair 40 of gages for engaging opposite side edges of a sole, a clutch, actuating means therefore for including means for exerting a predetermined resistance against the throwing of the clutch into operation, means controlled 45 by the operator for pressing the gages against the sole and for gradually overcoming the resistance of the clutch actuating means, and a stop for limiting the pressure which can be applied to the sole by said 50 gages after the clutch has been thrown into operation.

26. In a machine for operating upon soles, the combination of a knife holder, two knife blocks mounted upon the holder, two 55 knives independently secured to the respective blocks, and a single clamping device for securing both blocks to the holder.

27. In a machine for operating upon soles, the combination of a knife holder, a pair 60 of knife blocks adjustably mounted upon opposite sides of the holder and a single clamping stud for securing both knife blocks in adjusted position to the holder.

28. In a machine for operating upon soles, 65 the combination of a knife holder, a pair of knife blocks each provided with an adjusting screw, a pair of knives secured to the respective blocks, a single clamping stud for securing both knife blocks in adjusted position on the holder, and means for reciprocating the holder.

In testimony whereof I have signed my name to this specification.

FREDERIC E. BERTRAND.
